UNITED STATES PATENT OFFICE.

EDWARD F. YULKE, OF NEW YORK, N. Y., ASSIGNOR TO CONTINENTAL PAPER BAG COMPANY, OF NEW YORK, N. Y., A CORPORATION OF MAINE.

EGG-CARTON CARRIER.

1,158,095.

Specification of Letters Patent. Patented Oct. 26, 1915.

Application filed November 18, 1914. Serial No. 872,675.

To all whom it may concern:

Be it known that I, EDWARD F. YULKE, a citizen of the United States, and a resident of New York, borough of Brooklyn, in the 5 county of Kings and State of New York, have invented certain new and useful Improvements in Egg-Carton Carriers, of which the following is a specification.

The object of this invention is to provide 10 a safe and economical package for fragile articles, particularly for eggs in transportation, as for instance by parcel post.

The improved carton or package comprises broadly means for containing and holding 15 together a predetermined number of articles, and elastically supporting, preferably suspending, each article and separating them one from another and for elastically supporting such container and safeguarding the 20 same and its contents against shocks and blows.

In the accompanying drawings a practicable carrying out of my invention is shown by way of illustration, in which drawings—

25 Figure 1 is an edge view or side elevation of my improved casing. Fig. 2 is a top view of the same. Fig. 3 is a central cross section of said casing. Fig. 4 is a perspective view of my improved casing, partly 30 broken away, and containing a carton of eggs ready for shipment. Fig. 5 is an enlarged central cross section of the device containing a carton of eggs. Fig. 6 is a perspective view of the principal member of 35 my improved casing, partially folded into shape; and Fig. 7 is a central cross section of a modification of my improved casing adapted to carry two egg cartons inclosed within the same.

40 In the transportation of articles of a fragile nature or those easily injured, it is desirable, particularly if the means of transportation is liable to expose the articles to shocks or blows, as for instance by parcel 45 post, to hold the articles separated one from another and to elastically suspend them. It is also desirable, in the means of transportation mentioned, that articles which upon injury will permit the escape of substances 50 injurious to other packages, be so packed that in the event of damaged articles being inadvertently placed in the package, such substance escaping from the articles will be prevented from escaping from the package.

55 Many articles of merchandise are invari-

ably sold in quantities of a certain unit of count, for instance eggs by the dozen. By providing a packaging device which will receive and contain just the unit, or a multiple of the same and will clearly display the 60 fact of a short count the shipper and receiver are both saved the task of counting the articles and can readily detect the abstraction of any in transit.

In the illustrative example shown in the 65 drawings the inner casing 1 is in the form of an egg carton designed for use in packing eggs when the carrying of them is not liable to expose them to severe or rough treatment. Such carton has an outer wall or shell 2 70 which carries a series of pockets or nests formed in a medially disposed partition. The partition is composed of two superposed sheets, preferably card board, 3, 3. The positioning devices, shown in the form 75 of pockets or nests, are formed of a series of flaps or fingers 4 extending outwardly from both sheets or partition members. The egg carton preferably is provided with the number of nests or pockets corresponding to the 80 unit of count by which the intended contents of the package are usually supplied to particular markets. The pockets are disposed preferably in two rows covered by a housing and between the rows the outer wall or shell 85 2 constituting the housing is creased on each side. The inner face of the wall at the bottom of the crease is shown in contact with the adjacent partition sheet or member 3, 3. Such formation, among other things, divides 90 the interior of the carton into two compartments. The flaps or fingers 4 are of such form and proportions that the intended articles are supported, and if not too small, suspended elastically. The partition 3, 3 is 95 shown securely supported at each side of each row of article positioning devices.

The inner carton is shown held in its closed position by a string 7 having a suitable fastening 8. The outer casing designated in a general way by 9, is shown formed of a sheet of material, preferably card board, see Fig. 6, for inclosing the inner carton and elastically suspending the same. When in position on the inner carton the outer 105 casing presents a crease 10, or the equivalent thereof when the edges 10¹, 10¹ are brought together, entering the crease 5 on the respective side of the inner carton and preferably bottoming therein and engaging 110

the major portion of the faces thereof. This will permit the outer casing to engage the inner carton near the center of gravity thereof. The casing 9 herein illustrated, envelops the inner carton 1 exposing the ends only. These are covered by a retainer 11 within which the casing 9 telescopes. This retainer closes the ends of the casing 9 and the open sides of the creases 10 and holds the casing 9 in its folded position around and supporting the inner carton.

It will be seen that an outer wall is provided spaced from the inner egg carton so that a denting blow of considerable force 15 can be given the package without bringing the outer wall in contact with the inner carton. The creased portion of the outer casing 9 is shown notched at 12 for engaging the binding cord 7 and elastically relatively 20 positioning the two casings longitudinally. The binding cord 7 and notches 12 are preferably centrally located.

It is frequently desirable to ship in a single package a multiple of the unit of 25 count, but nevertheless employ the primary carton. The present invention contemplates the enlargement of the outer casing to contain a plurality of the inner cartons 1. This is illustrated in Fig. 7 where the outer casing 9¹ is shown provided with two pairs of creases or ridges 10² each pair suspending a self contained package of articles, and the casing 9¹ telescoped within an outer retainer 11¹.

30 Of course it will be apparent that the form of the device shown in the drawings and described herein is illustrative of my invention and that changes may be made as occasion may demand.

35 I claim:

1. The combination of an inner carton and an outer casing, the inner carton containing means for elastically suspending and separating a plurality of articles and being 40 elastically suspended within the outer cas-

ing, the outer casing engaging the inner carton inwardly of the side walls thereof.

2. The combination of a carton having creases in its sides and a casing surrounding the same, and having ridges seated in such 50 creases for suspending the carton.

3. The combination of a carton having creases in its sides, a binding cord surrounding the carton and crossing the creases, and a casing surrounding the same and having 55 ridges seated in such creases, said ridges having notches receiving the said binding cord.

4. The combination of a carton having creases in its sides, and a casing surrounding the same and having ridges seated in and 60 engaging the side walls of such creases for suspending the carton.

5. A device of the character specified comprising a card board folded blank having creases in its opposite sides forming ridges 65 adapted for entering suitable creases in a carton and suspending the same.

6. A device of the character specified comprising a card board folded blank having creases in its opposite sides forming ridges 70 for entering suitable creases in a carton, there being notches formed in said ridges for the reception of a binding cord on the said carton.

7. The combination of a carton having a 75 horizontal partition, article pockets carried thereby and a housing having creases formed in its sides, the bottoms of the creases engaging the respective sides of the partition, and an outer casing having creases forming 80 ridges seated in the creases formed in the sides of the carton.

Signed at New York, in the county of New York and State of New York this 16th day of November, 1914, before two subscribing 85 witnesses.

EDWARD F. YULKE.
